UNITED STATES PATENT OFFICE.

NANCY L. O. STILES, OF CLEVELAND, OHIO.

DESIGN FOR A BRUSH.

54,565.

Specification for Design.

Patented Mar. 2, 1920.

Application filed July 14, 1919. Serial No. 310,868. Term of patent 14 years.

To all whom it may concern:

Be it known that I, NANCY L. O. STILES, a citizen of the United States, residing at 1776 E. 93rd street, Cleveland, in the county of Cuyahoga and State of Ohio, have invented a new, original, and ornamental Design for a Brush, of which the following is a specification, reference being had to the accompanying drawing, forming part thereof.

Fig. II is a side elevation thereof.

Fig. III is a bottom plan view.

I claim:

The ornamental design for a brush as shown.

N. L. O. STILES.
